SET OF ORNAMENTAL INITIALS FOR JEWELRY

Felix P. Kinsley, 407 N. 8th St., St. Louis, Mo.

Continuation of design application Ser. No. 62,316, Sept. 30, 1960. This application June 29, 1961, Ser. No. 65,762

Term of patent 14 years

(Cl. D45—1)

FIG. 1.

FIG. 2.

FIG. 4

FIG. 3.

FIG. 5

FIG. 1 is a top plan view of one initial of the set of ornamental initials for jewelry, showing my new design;

FIG. 2 is a side view thereof;

FIG. 3 is a front view, on a reduced scale, of the other 25 letters of the alphabet comprising the set of ornamental initials for jewelry; all having substantially the same thickness as shown in FIG. 2;

FIG. 4 is a cross sectional view as seen along line 4-4 of FIG. 1; and

FIG. 5 is a perspective view thereof.

This application is a continuation of my earlier filed application, Serial No. D. 62,316, filed September 30,

1960, and now abandoned, entitled "Alphabet for Finger Ring Initials."

I claim:

The ornamental design for a set of ornamental initials for jewelry, substantially as shown and described.
